DESIGN FOR AN ARTIFICIAL CHRISTMAS TREE

John Frei, Jr., Chicago, Ill.

Application April 8, 1936, Serial No. 62,012

Term of patent 14 years

To all whom it may concern:

Be it known that I, John Frei, Jr., a citizen of the United States, residing at Chicago, in the county of Cook and State of Illinois, have invented a new, original, and ornamental Design for an Artificial Christmas Tree, of which the following is a specification, reference being had to the accompanying drawing, forming a part thereof, and in which:

Figure 1 is an elevational view of an artificial Christmas tree showing my new design; and
Figure 2 is a top plan view of the tree of Figure 1.

I claim:

The ornamental design for an artificial Christmas tree, as shown.

JOHN FREI, JR.
